UNITED STATES PATENT OFFICE.

JULIAN F. DENISON, OF NEW HAVEN, CONNECTICUT, ASSIGNOR TO GOTTFRIED PIEL, OF NEW YORK, N. Y.

FUEL-TANK.

1,271,675.

Specification of Letters Patent.

Patented July 9, 1918.

Application filed September 21, 1916. Serial No. 121,526.

To all whom it may concern:

Be it known that I, JULIAN F. DENISON, a citizen of the United States, and resident of New Haven; in the county of New Haven 5 and State of Connecticut, have invented certain new and useful Improvements in Fuel-Tanks, of which the following is a specification.

My invention relates in general to gravity 10 flow controlled liquid feeding device designed to constitute an attachment for installation in a liquid supply line, and particularly designed to be installed in the fuel supply pipe leading from the fuel reservoir 15 to the carbureter of an internal combustion engine such as is used in automobile power plants.

In one type of gravity feed fuel supply devices for automobiles the fuel tank is placed 20 below the level of the carbureter and the liquid elevated in order that the fuel may flow by gravity to the carbureter.

The difficulty which has heretofore existed in insuring a positive feed in exact accordance with the different speed requirements 25 of the engine has been solved somewhat by pumping the liquid into an auxiliary tank and to control the flow by means of floats in the auxiliary acting upon certain flow 30 controlling valves disposed in the pipe line. These valves introduce objectionable features in that they are apt to leak, must be adjusted frequently, are prone to stick or work spasmodically, and are expensive to 35 construct and install.

Accordingly, one of the objects of my invention is to provide a valveless device for insuring a positive and constant flow to the carbureter, independent of any irregularity 40 in the rate at which the fuel is caused to be drawn by the carbureter.

I attain this object broadly by providing a supplemental reservoir tank free of controlling valves, positioned above the level 45 of the carbureter and arranged so that the liquid may flow freely from the tank to the carbureter similar to such devices now known, but to supply the liquid to the tank at a rate greater than the maximum possible 50 demand on the tank by means of a type of pump which will automatically cease to function after a predetermined amount of liquid has accumulated in the tank.

The invention also contemplates the use

of a closed auxiliary tank for the purpose 55 of forming a pressure condition therein so that the gravity flow may normally be assisted by some positive pressure. The lowering of a liquid level, however, in a closed tank may under some circumstances tend to 60 form a vacuum condition in the tank which would affect the gravity flow therefrom. To prevent any such interruption to the free outward flow from the tank, the invention 65 contemplates the providing of release means for insuring a pressure on the liquid in the tank at least equal to the external air pressure affecting the carbureter or other exhaust outlet from the tank.

Various other objects and advantages of 70 the invention will be in part obvious from an inspection of the accompanying drawings and in part will be more fully set forth in the following particular description of one 75 form of mechanism embodying my invention, and the invention also consists in certain new and novel features of construction and combination of parts hereinafter set forth and claimed.

In the drawings.

Figure 1 is a side elevation of a preferred embodiment of my invention;

Fig. 2 is a similar view, looking from the right hand side of Fig. 1, with part of the tank shell broken away to show internal 85 construction;

Fig. 3 is a view similar to Fig. 2, with the lower portion thereof taken in axial section at right angles to the view shown in Fig. 2;

Figs. 4 and 5 are horizontal transverse 90 sectional views taken respectively on the lines 4-4 and 5-5 of Fig. 3, looking in the direction indicated by the arrows.

The device is shown conveniently constructed of two readily detachable parts, including a lower mechanism containing hollow casting 6, constituting a support for a spun metal shell 7 positioned thereon and coacting therewith to form a liquid receiving reservoir 8. This reservoir has a capacity 95 sufficient to contain an amount of surplus liquid to supply any abnormal demands on the system.

The casting includes a flat cylindrical upper portion 9, with the upper face thereof recessed to form a well 10, constituting the lower portion of the reservoir. The casting is provided with an out-turned peripheral

- flange 11, constituting a support for the lower open end of the shell 7. The open end of the shell is defined by an outstanding flange 12, interposed between which flange is 5 a gasket 13. The shell and casting are fastened together by means of screws 14 passed through the flange of the shell and through the gasket into engagement with the flange of the casting.
- 10 One side of the cylindrical portion 9 of the casting is enlarged to form a depending extension 15, which extends diametrically of the casting, and terminates in an enlarged cylindrical head 16 depending from and positioned adjacent one edge of the portion 9. The head 16 is recessed from its outer face to provide a housing 17 for a two-bladed rotary pump 18 of conventional design.
- The extension is drilled diametrically of 20 the portion to provide a bearing 19 for a pump shaft 20 driven by a pulley 21 and operatively connected to the pump to actuate the same, as is usual with devices of this character. The recess forming the housing 25 17 has its outer side closed by means of a face plate 22 fastened to the head 16 by means of screws 23, arranged so that the removal of the screws and plate provides ready access to the operative elements of the pump 30 and facilitates the removal of the blades and pump shaft.
- The pump is provided with a depending inlet pipe 24, constituting an integral part of the casting, and in fluid communication with 35 a source of liquid supply usually disposed below the level of the tank and indicated diagrammatically by the L-nipple 25. The exhaust from the pump is provided by means of a vertically disposed L-passageway 26 40 (see Fig. 3), contained within an extension 27 forming an integral part of the casting within the outline of the well forming recess and extending from the wall thereof toward the center, as shown more particularly in 45 Figs. 4 and 5.
- An outlet pipe 28 extends upwardly into the shell 7, has its lower end 29 threaded into the up-turned inner end of the passageway 26, and has its upper end provided with a 50 plurality of outlet vents 30 positioned adjacent the top wall of the shell. The tank is provided with an outlet 31 in the form of a passageway drilled through the extension 27, to the lower end of which extension 55 is attached the outlet nipple 32, designed to constitute a coupling for the pipe which leads the fuel to the carbureter.
- In order to increase the normal depth of the well of liquid retained in the tank during the period when the pump is inoperative, a relatively short outlet pipe 33 is threaded into the outlet 31, with its intake end terminating within the tank but below the level 60 of the outlet vents 30.
- 65 The extension 27 is provided with a by-
- pass 34, opening from the tank below the level of the outlet pipe, and leading into the passageway 26, past a control valve 35. This control valve is maintained normally in closed position, intercepting the passage 70 of the liquid through the by-pass, and in the form of the device illustrated (see Fig. 4) is shown to be a frusto-conical valve engaging a similarly shaped valve seat and maintained in seated position by a coil spring 75 36 guided on the valve stem 37 with one end thereof bearing upon the valve and the other end thereof bearing upon a plug 38 threaded into the outer end of a compartment 39' drilled into the extension 27 for the 80 purpose of accommodating the valve parts.
- The valve stem extends through the plug to provide a handle 39, by means of which the valve may be moved into unseated position against the tension of the spring, so as 85 to permit a flow from the well through the by-pass for the purpose of priming the pump.
- The tank is normally closed, but in order to permit an equalization of pressures in case 90 the pressure within the tank is lowered from normal, an air inlet valve 40 is provided in the upper end of the shell 7, and above the normal liquid level in the tank. This valve construction includes a bushing 41 fixed to 95 the tank and constituting an opening into the tank. A valve casing 42 is threaded into the bushing and acts to close the opening. The casing is provided with an inwardly facing frusto-conical valve seat 43. A similarly shaped valve 44 is maintained in position closed on said seat by means of a coil spring 45 contained within a chamber 46 formed within the valve casing. One end of the spring rests on the bottom of the 100 chamber, and the other end bears on an adjustable stop 47 threaded on the valve rod 48. The pump shaft is provided with a suitable oil cup 49.
- In operation it will be understood that the 110 device is installed in position in the fuel feed line with the inlet to the pump connected to a suitable source of fuel supply, and the outlet nipple connected to a carbureter or similar device fed from the system, which 115 device is positioned below the tank so that the flow through the outlet will be gravitational.
- Assuming that the pump is suitably primed, the actuation of the pulley from 120 some suitable source of power will cause the pump blades to rotate, thereby to draw in the liquid through the pump inlet and pass the same therefrom into the tank through the outlet vents, as particularly shown in 125 the arrows in Fig. 2, and as is common with the actuation of rotary pumps now in general use. The level of the liquid in the tank will rise and overflow through the outlet, and it will be obvious that this flow will be 130

5 maintained as long as the liquid in the tank is above the level of the outlet pipe. As long as this condition persists, the flow through the outlet will be uniform and sufficient to meet any demands thereon by the carbureter or other device supplied therefrom.

10 As the pump has a capacity for supplying the liquid to the tank at a rate in excess of any possible rate at which it can be withdrawn, it will be understood that the liquid will rise in the tank, placing the air therein under compression, thus insuring a positive ejection of the liquid through the outlet, in addition to the flow controlled by 15 the action of gravity.

15 It will be obvious that the internal pressures in the tank, due to the progressively rising liquid therein, will reach a point having a force sufficient to resist the tendency 20 of the pump to eject more liquid into the tank. Under this condition, the pump will run idly, the blades merely rotating without drawing any more liquid from the main reservoir, and the flow into the tank will be 25 intercepted as long as any such abnormal pressure condition exists in the tank. The flow of liquid through the outlet will lower the liquid level in the tank, and automatically release the pressure condition, thus 30 permitting the pump to again functionate.

35 It is apparent that the lowering of the liquid level in the tank may tend to create a vacuous condition above the liquid level, and any such condition of course would interfere with the free flow through the outlet, especially where the outlet is open to the air. Any such reduction of pressure, however, would cause an unbalancing action upon the air inlet valve, causing the 40 external air pressure to force the valve into open position, thus permitting the equalizing of the pressure within the tank to correspond to the external air pressure.

45 It is usually true of devices of this character that, when inoperative, the liquid collected in the tank tends to leak out either through the carbureter or through the pump. In order to conserve a supply sufficient to inaugurate the action of the 50 engine or other prime mover for driving the pump, the outlet pipe has its intake opening positioned some material distance above the bottom of the tank. Even though there may be a leak through the carbureter 55 it will still be about one-third filled with liquid. Leakage is also apt to occur, though perhaps not to the same extent, through the pump, but usually the pump will retain an amount of the liquid to insure its prompt 60 actuation when started, even after a prolonged period of time.

65 Any leakage through the pump must necessarily be past the valve controlling the bypass, but it must be considered that this valve is seldom used, and therefore is sub-

jected to but little wear. It can be ground to have a snug fluid-tight fit on its seat, and the retaining spring may be made as strong as desired. In this way possible leakage past the pump is reduced to a minimum, if 70 not entirely eliminated, and there is retained an ample amount of liquid at least to prime the pump and carbureter.

75 However, should it be necessary to introduce liquid in order to prime the pump and carbureter the valve handle is drawn forwardly, thus unseating the valve and permitting the liquid to flow from the well into the pump, so that the succeeding actuation of the pump will promptly cause a flow of 80 liquid to pass into the tank. Releasing the tension on the handle will cause the valve to re-seat, thus returning all parts to their normal operative position.

85 By means of a device of this character it is possible to insure a constant flow to the carbureter, uninfluenced by the demands on the tank or the rate at which the fuel is supplied to the tank. There is little if 90 any possibility of abnormal pressures accumulating in the tank, or any of the other objections prevalent in pressure controlled systems now in general use. The device is always in condition to respond promptly to the inauguration of the pump action, and 95 even if the tank should be emptied of sufficient fuel to prime the pump, the air valve may be readily unscrewed from its seat, thus providing an inlet to introduce a small portion of priming liquid.

100 The form of air inlet disclosed permits of both an air controlled valve and a priming inlet in the same construction, thus minimizing the possibility of leakage at this point.

105 In some types of devices it is desirable to provide an inverted U pipe 4 between the main reservoir and inlet 25 to the pump and to have the crotch portion extend above the normal liquid level in the tank. This 110 construction insures a priming of the pump as the tank and last reach of the U pipe forms a U-tank with the pump disposed therein. If desired a check valve 50 may be positioned in the first reach of the pipe 115 49' to eliminate any possibility of the liquid siphoning out of the tank.

120 Another modified construction contemplates a depending overflow or by-pass pipe 51 leading out of the side of the tank above a normal maximum liquid level and the lower end 52 of which is arranged to be connected to the intake of the pump or may even lead back to the main fuel reservoir.

125 Having described my invention, I claim:

1. A device designed to constitute an insert in a liquid feed line, comprising means for elevating the liquid, a reservoir for receiving the elevated liquid, and an outlet 130

- from the reservoir for permitting the liquid to flow therefrom by gravity, said elevating means including a rotary pump having a capacity sufficient to supply the reservoir at a rate in excess of the rate of flow therefrom.
2. A device designed to constitute an insert in a liquid feed line, comprising a pump for elevating the liquid, a reservoir for receiving the elevated liquid, a continuously open passageway connecting the pump with the reservoir, an outlet from the reservoir for permitting the liquid to flow therefrom by gravity, said pump supplying the reservoir at a rate in excess of the rate of flow therefrom, and said pump controlled by the presence of a definite volume of liquid in the reservoir for causing the pump to work idly and thus intercept the discharge into the reservoir of any liquid in excess of said definite volume.
3. A device designed to constitute an insert in a liquid feed line, comprising a pump for elevating the liquid, a reservoir for receiving the elevated liquid, a continuously open passageway connecting the pump with the reservoir, an outlet from the reservoir for permitting the liquid to flow therefrom by gravity, said pump supplying the reservoir at a rate in excess of the rate of flow therefrom, and means for maintaining a pressure on the liquid in the tank at least equal to the external pressure whereby the outflow is maintained.
4. A device designed to constitute an insert in a liquid feed line, including a pump for elevating the liquid, a valveless conduit for conducting the liquid free of the pump, means for insuring a constant gravitational flow from said elevated liquid independent of the rate at which it is elevated, and means for constantly driving the movable element of the pump at all levels of the elevated liquid.
5. In a device of the class described, a tank provided with a casting constituting a bottom, an outlet therefrom positioned above the bottom so as to form a well in the tank, said casting provided with an outlet leading from said well, means opening into the tank above the level of the outlet for supplying liquid to the tank, a cylindrical removable shell for constituting the upper portion of the tank, and means for fastening the shell to the casting.
6. In a device of the class described, a tank provided with a bottom, a pump positioned in said bottom, an outlet therefrom positioned above the bottom so as to form a well in the tank, means carried by the bottom and opening into the tank above the level of the outlet for supplying liquid to the tank, and a by-pass in the bottom opening from the well below the level of the outlet into the pump whereby the liquid re-
- maining in the well may be drawn off through the pump.
7. In a device of the class described, a tank provided with a bottom, an outlet therefrom positioned above the bottom so as to form a well in the tank, means carried by the bottom and opening into the tank above the level of the outlet for supplying liquid to the tank, a by-pass in the bottom opening from the well below the level of the outlet whereby the liquid remaining in the well may be drawn off, a pump priming conduit contained within the outlines of the bottom and opening from said by-pass, and means for controlling said by-pass.
8. In a device of the class described, a tank, including a single casting constituting the bottom of the tank, a shell supported from the casting and constituting the upper portion of the tank, and a rotary pump mounted in said casting and having a discharge therefrom leading into the interior of the tank, said casting provided with a pair of passageways therein, one of said passageways constituting an inlet to the pump, and the other constituting an outlet from the interior of the tank, and means for rotating said pump.
9. In a device of the class described, a tank, including a casting constituting the bottom of the tank and provided with a recess designed to accommodate a pump element, said casting provided with a passageway leading into said recess to constitute the inlet to the pump, said casting provided with a second passageway for leading the fluid from the pump to the interior of the tank, and also provided with a recess adapted to provide a shaft bearing leading to the pump recess.
10. In a device of the class described, a tank, including a casting constituting the bottom of the tank and provided with a recess designed to accommodate a pump element, said casting provided with a passageway leading into said recess to constitute the inlet to the pump, said casting provided with a second passageway for leading the fluid from the pump to the interior of the tank, and also provided with a third passageway constituting an outlet therethrough from the tank interior, said casting provided with a shaft bearing leading to the pump recess for mounting an actuating shaft for the pump element.
11. In a device of the class described, a tank, including a casting provided with a recess designed to accommodate a pump element, said casting provided with a passageway leading into said recess to constitute the inlet to the pump, a demountable cover plate for closing said recess and arranged to provide ready access to the pump element from the outside of the tank, and a pump element mounted in said recess.

12. In a device of the class described, a tank normally air-tight, a pump for supplying liquid to said tank, a fluid outlet from said tank, said tank provided with a bushing fitting into the upper portions thereof, a valve casing demountably fitted into said bushing and constituting an air inlet opening into the tank above the normal liquid level therein, and a valve carried by the casing and removable therewith from the bushing normally closing said air inlet and opened by a pressure condition therein lower than the external air pressure thereby to break any vacuum which may form in the tank.
13. In a device of the class described, a normally closed tank provided with a liquid inlet and an outlet therefrom, means capable of forcing the liquid into said tank through the inlet at a rate greater than the rate of outflow through said outlet thereby to act on the entrapped air in the tank to place the same under pressure, means for breaking any vacuum which may form in said tank, said means including an air inlet to the air space therein above the liquid level, and a valve held in closed position by the air pressure in said space and opened by a pressure condition therein lower than that of the external atmosphere.
14. In a device of the class described, a supply tank provided with a liquid inlet and an outlet therefrom, a pump constantly open to said tank and tending to create a pressure therein greater than the external atmospheric pressure, and means controlled by a pressure condition in the tank lower than that of the external atmosphere for opening the tank to the outside air and thus relieve any accidental vacuum conditions which may form in said tank.
15. In a device of the class described, a normally closed tank provided with a constantly opened outlet therefrom, an open inlet to the tank free of valves, and means for forcing liquid into the tank, said means having a capacity for forcing the liquid into the tank at a rate greater than it can flow from the tank.
16. In a device of the class described, a normally closed tank provided with an outlet therefrom, an inlet to the tank, and means for forcing liquid into the tank, said means having a capacity for forcing the liquid into the tank at a rate greater than it can flow from the tank, and said means arranged to run idly whenever the supply to said tank is intercepted by the pressure condition therein.
17. In a device of the class described, a closed tank provided with a liquid outlet therefrom, a rotary pump for supplying liquid to said tank, an uninterrupted passageway between said pump and tank, said pump having a capacity for supplying the liquid at a rate greater than it can be withdrawn, and said pump designed to rotate idly when the tank is full, and normally closed valvular means controlled by a lowered pressure condition in said tank for restoring normal pressure therein so as to permit the admission of the liquid from the pump.
18. In a liquid feed line, means for supplying a constant feed through said line, said means including a rotary pump having a pumping capacity sufficient to supply any drawing demands on the feed line, constantly acting means for actuating said pump, a reservoir for receiving surplus liquid, said reservoir and pump coacting to constitute a means controlled by pressure in said reservoir for intercepting the admission of any excessive amount of liquid from the pump.
19. In a liquid feed line, means for supplying a constant feed through said line, said means including a continuously acting pump having a pumping capacity more than sufficient to supply any drawing demands on the feed line, a reservoir for receiving surplus liquid, said reservoir and pump coacting to constitute a means controlled by pressure in said reservoir for regulating the amount of liquid admitted into the reservoir from the continuously acting pump.
20. In a device of the class described, a normally closed tank, and a rotary pump adjacent the bottom of the tank for supplying liquid thereto, said tank provided with a pump housing for containing the rotary element of the pump, said housing having an inlet for supplying liquid to the same for the purpose of priming the pump, and means for controlling said inlet.
21. In a device of the class described, a normally closed tank, a pump adjacent the bottom of the tank for supplying liquid to the same and adapted to be primed from said tank, and a valve positioned in the upper part of the tank for automatically breaking a reduced pressure condition therein, said valve being bodily removable from the tank so that the opening for the valve may be utilized as a liquid inlet to prime the pump.
22. In a device of the class described, a tank provided with an inlet passageway and a normally open outlet therefrom, a pump for supplying liquid to said tank through said inlet passageway, a separate passageway leading from the tank back to the pump for the purpose of leading a priming liquid from the tank to the pump, and a normally closed valve for controlling said separate passageway.
23. In a device of the class described, a tank provided with a bottom casting having straight drillings forming an outlet and an inlet passageway, said casting hav-

ing an enlarged portion adapted to house a pump for supplying liquid to said tank through said passageway, a separate passageway leading from the tank for the purpose of leading a priming liquid from the tank to the inlet passageway and a normally closed valve housed within the tank for controlling said separate passageway.

24. In a device of the class described, a

tank, a pump for supplying liquid to said tank, an outlet leading downward from said tank, and an inverted U pipe constituting the inlet supply pipe leading to the intake of said pump.

Signed at New Haven, in the county of 15
New Haven, and State of Connecticut, this
15th day of September, A. D. 1916.

JULIAN F. DENISON.
